UNITED STATES PATENT OFFICE.

HENRY WILLSON, OF CHICAGO, ILLINOIS.

INK-FOUNTAIN FOR PRINTING-PRESSES.

SPECIFICATION forming part of Letters Patent No. 279,301, dated June 12, 1883.

Application filed October 23, 1882. (No model.)

To all whom it may concern:

Be it known that I, HENRY WILLSON, of Chicago, in the county of Cook and State of Illinois, have invented certain new and useful 5 Improvements in Ink-Fountains for Printing-Presses, of which the following, in connection with the accompanying drawings, is a specification.

In the drawings, Figure 1 is a top or plan 10 view of an ink-fountain embodying my invention. Fig. 2 is a section in the plane of the line x x , and Fig. 3 is a section in the plane of the line y y .

Like letters of reference indicate like parts. 15 My invention relates to that class of ink-fountains in which inks of different colors are separated from each other, but supplied to the same inking-roller. It is frequently desirable and necessary that the ink - compartments 20 should be varied in width; and the purpose of my invention is to provide means whereby this variation or adjustment may be accomplished with facility.

In the drawings, A A represent the sides of 25 the ink-fountain; B, the fixed bottom; C, the adjustable bottom; D D, the adjusting-screws; E, the primary ink-roller, and F F are the partitions for dividing the fountain into separate compartments. The parts now referred to are 30 old and well-known, so far as I am aware, and I do not therefore here intend to claim the same, broadly. The partitions F F are adjustable laterally, the width of the fountains being thereby made capable of being varied.

35 G G are removable blocks, varying from each other in width, some being very wide, others very narrow, and some only moderately wide, as shown. These blocks G G, I arrange between the upper or outer ends of the partitions F F, and I select such blocks as may

be suited to the space desired between those partitions—that is, after determining what space I may wish between any two of the partitions F F, I place those partitions the desired distance apart, and then arrange between their upper ends one or more blocks, G G, until the space between those ends is thus filled. I proceed in the same manner in setting the other partitions, and after all are set I lock the whole in place firmly by means 45 of the inclined or wedge blocks H H.

It will be perceived that by using or having ready for use a comparatively large number of blocks G G varying greatly in width, some being very narrow, as shown, the partitions 50 F F may be set with nicety and facility in any desired position. The width of the different compartments of the ink-fountain may thus be varied, so that inks of different colors will 55 be applied to the inking-rollers in stripes or 60 bars of different width.

Having thus described my invention, what I claim as new, and desire to secure by Letters Patent, is—

1. The combination, in an ink-fountain for 65 printing - presses, of the laterally-adjustable partitions F F and the separating-blocks G G, made in various widths, substantially as and for the purposes specified.

2. The combination, in an ink-fountain for 70 printing - presses, of the laterally-adjustable partitions F F, the separating-blocks G G, varying from each other in width, and the inclined or wedge-shaped clamping-blocks H H, substantially as and for the purposes specified. 75

HENRY WILLSON.
